COMBINED SUPPORT AND SPACER FOR BARS

Ernest H. Geyer and Marion R. Geyer,
Chicago, Ill.

Application May 19, 1941, Serial No. 394,210

7 Claims. (Cl. 94—18)

The present invention relates generally to combined supports and spacers for bars. More particularly the invention relates to that type of combined support and spacer which is designed and especially adapted for use in connection with the formation of a concrete structure, such, for example, as a slab type roadway on a subgrade, and comprises a series of equidistantly spaced chairs which are formed of sheet metal strips and consist of seat forming or holder parts for a series of parallel horizontally extending bars, and pairs of downwardly divergent legs for supporting the holder parts in an elevated position with respect to the subjacent supporting surface or subgrade.

One object of the invention is to provide a combined support and spacer which is an improvement upon, and has certain advantages over, previously designed combined bar supports and spacers and is characterized by the fact that it effectively and efficiently fulfills its intended purpose and not only is durable and exceptionally sturdy but also is capable of being fabricated at a low and reasonable cost.

Another object of the invention is to provide a combined bar support and spacer of the type under consideration in which the equidistantly spaced chairs are of improved design and construction and have short horizontally disposed outwardly extending integral feet on the legs thereof that extend in one direction and have comparatively long horizontally disposed outwardly extending integral feet on the other legs thereof.

Another object of the invention is to provide a combined support and spacer of the last mentioned character in which the outer end of the long foot of each chair is disposed beneath, and is connected in a novel manner to, the short foot and the inner portion of the long foot of the adjoining chair and serves as a medium for holding the legs of said adjoining chair in fixed relation.

A further object of the invention is to provide a combined support and spacer of the aforementioned type which is adapted in connection with a like support and spacer, to form an improved or novel type of unit for supporting a concrete roadway joint prior and during pouring roadway slab forming concrete at the sides of the joint.

A still further object of the invention is to provide a combined bar support and spacer which is capable of being quickly and readily assembled with respect to the bars to be supported and retained in place and serves when in its operative position to hold the bars in a truly parallel position.

Other objects of the invention and the various advantages and characteristics of the present combined bar support and spacer will be ap-

parent from a consideration of the following detailed description.

The invention consists in the several novel features which are hereinafter set forth and are more particularly defined by claims at the conclusion hereof.

In the drawings which accompany and form a part of this specification or disclosure and in which like numerals and letters of reference denote corresponding parts throughout the several views:

Figure 1 is a fragmentary perspective view of a roadway joint supporting unit consisting of two combined supports and spacers embodying the invention;

Figure 2 is a vertical longitudinal section through one of the combined supports and spacers illustrating in detail the arrangement and the design of the long feet of the chairs and showing the manner in which they are secured in place and form a chord or base for the support and spacer;

Figures 3, 4 and 5 are vertical transverse sections taken respectively on the lines 3—3, 4—4 and 5—5 of Figure 2; and

Figures 6, 7, 8, 9 and 10 are perspective views showing the manner in which each of the chairs is formed.

The invention is exemplified in a unit for use in connection with a roadway joint consisting of a filler strip S of compressible material and a series of parallel horizontally extending load transfer bars B. The joint is adapted for disposition between a pair of adjoining roadway forming slabs (not shown) and, as well understood in the art, permits the slabs to expand and contract in response to temperature changes or variations. The strip S is adapted to assume an upstanding or vertical position between the slabs. The load transfer bars B are spaced equidistantly apart. They extend through holes in the filler strip S and are held by the improved unit in parallel relation with the subgrade on which the roadway forming slabs rest. They are similar in design and construction and each consists of a sheet metal sleeve b, a dowel rod b¹ in the sleeve, caps b² at the ends of the sleeve and a pair of wing equipped stamping type stress reducers b³ on the inner portions of the ends of the sleeve. The central portions of the sleeves b of the load transfer bars B are weakened and fit within the holes in the compressible filler strip S. The dowel rods b¹ extend across the central portions of the sleeves b and are shorter in length than the sleeves in order that the ends thereof terminate inwardly of the caps b². The ends of the sleeves become bonded to the slabs upon hardening or setting of the concrete. When the slabs contract the weakened central portions of the sleeves rupture with

the result that the ends of the sleeves are free to slide on the ends of the dowel rods. The stress reducers b^3 , like the ends of the sleeves, become bonded to the slabs after setting of the concrete. They are located on opposite sides of the compressible filler strip S , as shown in Figure 1, and serve to reenforce the portions of the concrete that surround the ends of the sleeves b .

The unit serves to hold the joint in place during pouring of the concrete at the sides of the filler strip S in connection with formation of the slabs. It is adapted to become permanently associated with, and also to reenforce, the concrete and consists of a pair of combined bar supports and spacers 6 and 7 and a series of cross strips 8 . The combined support and spacer 6 is located at one side of the compressible filler strip S of the joint and serves to support the adjoining ends of the load transfer bars B . The other combined support and spacer, that is, the combined support and spacer 7 , is located at the other side of the strip S and is associated with, and serves to support, the other ends of the bars B . The cross strips extend between the combined supports and spacers 6 and 7 and serve, as hereinafter described, to hold them in laterally spaced relation.

The combined support and spacer 6 extends in parallel relation with the compressible filler strip S of the joint and consists of a series of equidistantly spaced chairs 9 . The latter correspond in number to, and are associated respectively with, the load transfer bars B of the roadway joint. They are formed of sheet metal stampings and consist of tubular seat forming or holder parts 10 and pairs of downwardly divergent legs 11 and 12 . The holder parts 10 are carried by the legs 11 and 12 so that they are disposed in an elevated position with respect to the subgrade and are in alignment with the bar holes in the strip S . They are in the form of three-quarter round bands and have substantially cylindrical interiors which serve as seats or pockets for the adjoining ends of the sleeves b of the load transfer bars B . The legs 11 of the chairs are straight and extend downwardly and outwardly in one direction. The other legs, that is, the legs 12 , are also straight and extend downwardly and outwardly in the opposite direction. The lower ends of the legs 11 embody integral outwardly extending feet 13 and these feet, as shown in Figures 1 and 2, are comparatively short and extend horizontally. The lower ends of the legs 12 of the chairs embody integral outwardly extending feet 14 . Such feet extend horizontally and are substantially coplanar with the feet 13 . They are many times longer than the feet 13 and serve as a medium for connecting together the chairs 9 of the combined support and spacer 6 . Preferably each foot 14 is twice as long as the space between the lower ends of the legs 11 and 12 . The central portions of the legs 11 are struck outwards to form longitudinally extending reenforcing ribs 15 and the central portions of the short feet 13 are struck upwards to form longitudinally extending reenforcing ribs 16 . The ribs 15 are full length and extend from the inner ends of the ribs 16 to the holder parts 10 . The central portions of the legs 12 of the chairs 9 are struck outwards to form reenforcing ribs 17 and the central portions of the feet 14 are struck upwards to form longitudinally extending reenforcing ribs 18 . The ribs 17 are full length and extend from the inner ends of the ribs 18 .

to the holder parts 10 . The ribs 18 serve to prevent bending or distortion of the feet 14 and extend between the inner or root portions of such feet and the outer extremities. As shown in Figures 1 and 2, the outer end of each foot 14 is arranged or positioned so that it underlies the short foot 13 and the inner portion of the long foot of the adjoining chair 9 and bridges the space between the lower ends of the legs of such adjoining chair. In order to interlock the chairs 9 so as to hold them in proper laterally spaced relation the outer extremities of the reinforcing ribs 18 are shaped to form hollow hemispherical head-like enlargements 19 and the portions of said ribs that are substantially midway between the inner root portions of the feet 14 and the outer extremities or ends of said feet are shaped to form upwardly extending hollow hemispherical head-like enlargements 20 . The enlargements 19 are shaped to fit within hollow hemispherical enlargements 21 and the enlargements 20 are shaped to fit within, and interlock with, hollow hemispherical enlargements 22 . The enlargements 21 are formed as parts of the inner portions of the reenforcing ribs 16 and the enlargements 22 are formed of parts of the reenforcing ribs 16 of the short feet 13 . In assembling the combined support and spacer 6 the chairs 9 are first arranged in series form. Thereafter the long foot 14 of each chair is manipulated or positioned so that it underlies the feet of the next adjoining chair and its enlargements 19 and 20 are in interfitting relation with the enlargements 21 and 22 of the feet of the next adjoining chair. As soon as the long feet 14 are brought into proper interlocking relation the chairs 9 are held in proper spaced relation. For the purpose of holding the enlargements 19 in interlocking or interfitting relation with the enlargements 21 at the inner or root portions of the ribs 18 locking clips 23 are provided. These clips, as shown in Figure 5, are in the form of sheet metal strips and underlie and extend transversely across the outer ends of the long feet 14 . The ends of the locking clips 23 are bent so that they extend upwards and then inwards. The upwardly extending portions of the ends of the clips are arranged in straddled relation with the side edges of the long feet 14 of the chairs and the inwardly extending portions overlie the inner ends of the feet 14 and thus serve to hold the enlargements 19 and 21 in seated or interlocked relation. The central portions of the clips 23 are struck upwards to form concavo-convex heads 24 and these fit within the enlargements 19 and serve to hold the clips 23 against longitudinal movement relatively to the long feet 14 of the chairs. The enlargements 20 and 22 are held in interlocked or interfitting relation by means of sheet metal clips 25 . These clips are the same in design and construction as the clips 23 . The central portions of the clips 25 underlie and extend transversely across the portions of the long feet 14 that are directly beneath the enlargements 20 and the ends of the clips 25 extend upwards and then inwards. The upwardly extending portions of said clips 25 are arranged in straddled relation with the adjacent side edges of the feet of the chairs and the inwardly extending portions overlie the side margins of the short feet 13 , as clearly shown in Figure 5. The central portions of the clips 25 have upstruck hemispherical heads 26 and these fit within the enlargements 20 and serve to

hold the clips 25 against longitudinal displacement. When the combined support and spacer 6 is fully assembled the chairs 9 are locked together in equidistantly spaced relation and the legs 11 and 12 thereof are effectively and efficiently held against lateral displacement due to the bridging action of the outer ends of the long feet 14. The long feet 14 and the short feet 13 of the chairs 9 constitute a chord or base for the combined support and spacer 6.

Each of the chairs 9 of the combined support and spacer 6 is formed as illustrated in Figures 6 to 10, inclusive. In forming each chair a strip of sheet metal is employed. Such strip, as shown in Figure 6, is of uniform width from end to end. In practice it has been found that but four steps are necessary to form each chair 9. The first step consists in taking the sheet metal strip and stamping one end thereof so that it has the shape or form which is shown in Figure 7. In the first stamping operation the strip is shaped to form the holder part 10, the rib equipped legs 11 and 12 and the short foot 13. As shown in Figure 7, the holder part 10 is flat and the legs 11 and 12 are coplanar and project in opposite directions from the holder part 10. In the first stamping operation the foot 13 is bent so that it has the proper angular position with respect to the leg 11. Due to the fact that the ribs 15 and 17 are formed in the legs 11 and 12 during the first stamping operation the two legs are of less width than the flat holder part 10. The ends of the two ribs 15 and 17 that are joined to the holder part 10 are arcuate. After the first stamping operation the other end of the sheet metal strip is subjected to a stamping operation in order to form the longitudinally extending rib 18 and the enlargements 19, 20 and 21. The second stamping operation results in completion of the long foot 14 of the chair. After the second stamping operation the enlargement 22 is formed in the reinforcing rib 16 of the short foot 13, as shown in Figure 9. To complete the chair the leg 11 is swung downwards into its proper or angular position with respect to the leg 12. Downward bending of the leg 11 causes the holder part 10 to be bent automatically into substantially cylindrical form, as shown in Figure 10 of the drawings.

The combined support and spacer 6 at the other or opposite side of the compressible filler strip S is exactly the same in design and construction as the combined support and spacer 6. It operates to support the adjoining ends of the load transfer bars B and consists of a series of equidistantly spaced chairs 27. The latter, like the chairs 9, are formed of sheet metal strips, as shown in Figure 1, the chairs 27 consists of three-quarter round holder members 28 and downwardly divergent legs 29 and 30. The holder members 28 are shaped to receive the adjoining or adjacent ends of the sleeves b of the bars B and are supported by the legs 29 and 30 in an elevated position with respect to the subgrade. The legs 29 extend in one direction and embody short feet 31. The other legs, that is, the legs 30, extend in the opposite direction and embody long feet 32. The latter correspond in length to, and are arranged in the same manner as, the feet 14 of the chairs 9. Each of the long feet 32 is arranged so that the outer end thereof underlies the short foot and the inner or root portion of the long foot of the adjoining chair, as shown in Figure 1. Interfitting en-

largements like the enlargements 19 and 21 and the interfitting enlargements 20 and 22 serve to secure the chairs 27 in connected relation. Clamp type sheet metal strips 33 and 34, like the clips 23 and 25, lock together the interfitting enlargements of the chairs 27.

The cross strips 8 for spacing apart the combined supports and spacers 6 and 7 are formed of sheet metal strips. The central portions of such strips underlie and extend transversely of the compressible filler strip S. The ends of the strips that are at one side of the filler strip are bent to form hooks 35 and these are arranged in hooked relation with the long feet 14 of the chairs 9, as shown in Figures 1 and 5. The other ends of the cross strips 8, that is, the ends at the other side of the compressible filler strip S, are bent or shaped to form hooks 36 and these are arranged in hooked relation with the long feet 32 of the chairs 30. The portions of the cross strips that are immediately inwards of the hooks 35 and 36 are struck upwards to form loop type ribs 37. Such ribs fit within the longitudinally extending ribs of the long feet of the chairs as shown in Figure 4, and serve to lock the combined supports and spacers 6 and 7 against inward movement. By reason of the fact that the ribs are in the form of loops the cross strips 8 are free to expand and contract in response to expansion and contraction of the roadway forming slabs in which the unit is embedded. By reason of the fact that the long feet of the chairs overlie the ribs 37 no concrete flows around such ribs in connection with formation of the slabs. Holes are formed in the strips 8 in order that nails or spikes may be driven through the strips into the subgrade in order to hold the unit in place.

In addition to the combined supports and spacers 6 and 7 and the cross strips 8 the unit comprises a strip 38. This strip is preferably formed of sheet metal and has equidistantly spaced holes 39. The latter are the same in diameter as the sleeves b of the load transfer bars B. The ends of the sleeves b that are supported by the chairs 30 extend through the holes 39 in the strip 38, as shown in Figures 1 and 2. Preferably the strip is located between the holder parts 28 of the chairs 27 and the adjacent stress reducers b³. When the strip 38 is in place it serves to prevent vertical flexure or bending of the combined supports and spacers 6 and 7. The strip constitutes simple means for preventing flexure of the unit while the latter is being manipulated into place over the subgrade preparatory to pouring concrete at the sides of the filler strip S.

In assembling the roadway joint and unit the load transfer bars B are first arranged in assembled relation with the compressible filler strip S. This is done by inserting the dowel rod carrying sleeves b through the holes in the strip S and then sliding the stress reducers b³ into clamped relation with said strip. After assembly of the bars B with respect to the compressible filler strip S the ends of the sleeves b at one side of the strip are inserted into the holder parts 10 of the chairs 9. After this operation the strip 38 is mounted on the other ends of the sleeves and such ends are inserted into the holder parts 28 of the chairs 27. At the conclusion of this operation or step the cross strips 8 are positioned under the long feet of the chairs and the ends or extremities are bent upwards and inwards to form the hooks 35 and 36. When the

roadway joint and unit are in place on the sub-grade concrete is poured at opposite sides of the compressible filler strip in order to form the roadway.

The herein described unit, due to its design and construction, may be assembled quickly and operates properly to hold in place the load transfer bars B. Because the combined supports and spacers 6 and 7 are formed for the most part of the chairs 9 and 21 the unit may be built up to any desired length. The unit as a whole is rigid and serves, after pouring of the concrete, to reinforce the roadway slabs.

Whereas the invention has been described in connection with a unit for supporting a roadway joint of the compressible filler strip and load transfer bar type it is to be understood that the invention contemplates as one embodiment thereof of a single combined support and spacer for general use in connection with a series of parallel horizontally extending bars. It is also to be understood that the invention is not to be restricted to the details set forth since these may be modified within the scope of the appended claims without departing from the spirit and scope of the invention.

Having thus described the invention what we claim as new and desire to secure by Letters Patent is:

1. A combined support and spacer for a series of parallel horizontally extending laterally spaced bars, comprising a series of laterally spaced chairs each bent from a single piece of sheet metal, consisting of a holder part for one of the bars, a pair of downwardly divergent legs extending downwards from the holder part, a short outwardly extending horizontal foot at, and formed integrally with, the lower end of one of the legs, and a long outwardly extending horizontal foot at, and formed integrally with, the lower end of the other leg, and having the outer portion of the long foot thereof underlying, and secured to, the short foot and the inner portion of the long foot of the adjoining chair.

2. A combined support and spacer for a series of parallel horizontally extending laterally spaced bars, comprising a series of laterally spaced chairs each in the form of a bent strip, consisting of a holder part for one of the bars, a pair of downwardly divergent legs extending downwards from the holder part, a short outwardly extending horizontal foot at, and formed integrally with, the lower end of one of the legs, and a long outwardly extending horizontal foot at, and formed integrally with, the lower end of the other leg, and having the outer end of the long foot thereof underlying, and interlocked by head and socket connections with, the short foot and the inner portion of the long foot of the adjoining chair.

3. A combined support and spacer for a series of parallel horizontally extending laterally spaced bars, comprising a series of laterally spaced chairs each in the form of a bent strip of sheet metal, consisting of a holder part for one of the bars, a pair of downwardly divergent legs extending downwards from the holder part, a short outwardly extending horizontal foot at, and formed integrally with, the lower end of one of the legs, and a long outwardly extending horizontal foot at, and formed integrally with, the lower end of the other leg, and having the outer end of the long foot thereof underlying, and interlocked by head and socket connections with, the short foot

and the inner portion of the long foot of the adjoining chair; and also comprising clips extending around the portions of the feet having the head and socket connections and serving together with said connections rigidly to secure or lock the chairs together.

4. A unit adapted to support a series of laterally spaced substantially horizontal bars and comprising a pair of combined supports and spacers arranged in opposed relation and at right angles to the bars and each including a series of chairs with holder parts for the adjacent ends of the bars and horizontal connecting members extending between and serving to connect said chairs and having longitudinal grooves in the under sides thereof, and sheet metal cross strips extending between and serving to cross connect said combined supports and spacers and having upstanding transverse loop type ribs at the ends thereof fitting within, and interlocked with, the grooves of said members.

5. A unit adapted to support a series of laterally spaced substantially horizontal bars and comprising a pair of combined supports and spacers arranged in opposed relation and at right angles to the bars and each including a series of chairs with holder parts for the adjacent ends of the bars and horizontal connecting members extending between and serving to connect the chairs and having longitudinally extending grooves in the under side thereof, and sheet metal cross members extending between and serving to cross connect said combined supports and spacers and having the ends thereof shaped to form hooks in hooked relation with said connecting members and having the portions thereof immediately inwards of their ends provided with upstanding transverse loop type ribs fitting within, and interlocked with, the grooves in said members.

6. That improvement in the manufacture of a bar supporting chair which comprises stamping a sheet metal strip to form a substantially flat central part and a pair of coplanar leg forming parts at the ends of the central part and with longitudinal centrally disposed out-struck full length reenforcing ribs, and then swinging one of the leg forming parts relatively to the other in a direction opposite to the direction in which the rib of said one leg forming part extends in order to bring them into a position wherein they extend at an acute angle with respect to one another and at the same time to cause the central part to be bent into a curved form so that it forms a holder for the bar.

7. That improvement in the manufacture of a bar supporting chair which comprises stamping a sheet metal strip of uniform width from end to end to form a substantially flat central part and a pair of coplanar leg forming parts at the ends of the central part and with longitudinal centrally disposed out-struck full length reenforcing ribs with curved and tapered inner ends, and then swinging one of the leg forming parts relatively to the other in a direction opposite to that in which the rib of the one leg forming part extends in order to bring them into a position wherein they extend at an acute angle with respect to one another and form the legs of the chair and at the same time cause the central part to be bent into a three-quarter round form wherein it forms the bar holding medium of the chair.
